WARE.

LOCOMOTIVE-BOILER FURNACE.

1,138,040.

Specification of Letters Patent.

Patented May 4, 1915.

Application filed December 18, 1911. Serial No. 662,349.

To all whom it may concern:

Be it known that I, CHARLES B. MOORE, a citizen of the United States, and a resident of the city of Evanston, Cook county, Illinois, have invented certain new and useful Improvements in Locomotive-Boiler Furnaces, of which the following is a specification.

My invention relates to improvements in locomotive boiler furnaces and has particular reference to improvements in refractory baffles, deflecting walls or so-called arches for the fireboxes of locomotive boilers.

The general objects of my invention are to provide a standard arch construction by means of which refractory arches may be easily installed in locomotive boiler fireboxes which vary in width, and with the use of a minimum number of brick forms of standard dimensions; which arch shall be of light weight and low cost; and which will materially enhance the commingling and admixing of the firebox gases for the purpose of producing substantially perfect combustion in the firebox.

A further object of my invention is to provide an arch structure or construction by means of which the arch proper may be located in the firebox at a height suitable to the specific conditions met with in the particular firebox in which the arch is being installed for producing the most economical results in fuel consumption, and by the use of firebricks of standard dimensions.

Further features and objects of my invention will be developed hereinafter.

My invention consists in an arch construction which includes a minimum number of patterns of refractory arch bricks and brick abutments so formed that the arch proper can be arranged in many different positions in the firebox; and further, by means of which arches can be installed in fireboxes of different widths extending from side to side therein without the necessity of having special bricks for each width of firebox.

My invention further consists in the various novel features of construction and in the combinations and arrangements of parts hereinafter fully described and particularly pointed out in the appended claims.

My invention will be more readily understood by reference to the accompanying drawings in which I have illustrated a pre-

ferred form of my invention together with several modifications thereof.

In said drawings: Figure 1 is a central longitudinal section of a locomotive firebox containing a front arch made in accordance with my invention; Fig. 2 is a horizontal longitudinal section of the firebox showing a plan view of the arch and taken on the line 2—2 of Fig. 1; Fig. 3 is a vertical transverse section of the firebox on the line 3—3 of Fig. 1; Fig. 4 is a view similar to Fig. 2 showing a slight modification of the form of arch proper; Fig. 5 is a transverse section of the firebox through the arch on the line 5—5 of Fig. 2; Fig. 6 is a transverse section taken on the line 6—6 of Fig. 4 showing a slight modification of the abutment members; Fig. 7 is a perspective view of the abutment member used in the preferred form of my arch as illustrated in Fig. 2; and Fig. 8 is a perspective view of the abutment member illustrated in Fig. 6.

My invention is capable of embodiment in different structures occupying various positions in the firebox and having different functions, and although I have chosen to confine the illustration of the invention to so-called "front arches" it should at once be understood that my invention is not thus limited.

Front arches in locomotive fireboxes have several functions, the main one being to provide a baffle in the path of the gases as they flow from the fuel bed to the flues and thereby retard their exit from the firebox and cause them to more evenly distribute their heat throughout the entire inner surface of the firebox. A further important function is to effect the intermingling of the various strata of gases and so cause more perfect combustion. These valuable functions together with others are preserved in arches made in accordance with my invention. A front arch usually occupies an inclined position in the firebox with its forward end in close proximity to or in abutment with the flue sheet, and it usually extends from side sheet to side sheet; it extends rearwardly from the flue sheet, and frequently as far as substantially the middle portion of the firebox so that the gases in passing around the rear end of the arch are forced to the rear portion of the firebox and consequently carry or distribute the heat to the rear end

of the crown sheet, as well as to the forward end thereof.

A locomotive boiler firebox, as illustrated, consists of a flue sheet 2, side sheets 3—3, a crown sheet 4 and a rear sheet 5 and is positioned within the boiler shell 6. It is provided with a grate 7 at its lower end. Flues 8 lead forward from the flue sheet and the rear sheet contains a fuel door or opening 9. The firebox, as illustrated in Figs. 1, 2 and 3, is equipped with two inclined water-circulating tubes 10, the same extending from the lower portion of the flue sheet upwardly and rearwardly to the rear sheet and serving to increase the circulation of water between the front and rear water legs of the boiler. In the type of boiler illustrated, these tubes are arranged at a comparatively slight distance from the side sheets of the firebox. In the different designs of locomotives the fireboxes vary more or less in width and for the purpose of installing arches in many different boilers it has been found necessary to carry an immense stock of firebricks of different dimensions and forms. This was proven to be expensive in that it required the carrying of large stocks of many forms of bricks at different points for the installation and the repairing of the arches. The present invention is directed to a form of construction which is particularly adapted for building arches in fireboxes of different widths and by the use of but two forms of bricks and the bricks are so formed that they interlock in many relatively different positions and in such a manner that the arch in any particular firebox can be readily placed in the position best adapted to produce the most economical results in fuel consumption.

As shown in the drawings, I make an adjustable arch by the use of two standard forms of brick, one of which A is an arch brick proper and the other B is an abutment brick. The abutment brick is formed to be supported in position against the side sheet of the firebox and its upper surface is formed in such a manner that when the arch brick proper is placed in position thereon their abutting surfaces will be interlocked in such manner that the arch brick proper will be held laterally in the firebox and also so that the outer end of the firebrick proper may be placed at several different distances from the side sheet and be retained in said position. The arch proper is made of a number of transverse rows of the bricks A, each row being made of two of these bricks which rest upon the oppositely disposed abutment bricks and incline inwardly and upwardly therefrom, their inner and upper ends abutting together at substantially the center line of the firebox and being formed to mutually interlock and retain each other in position. The abutment bricks B are pro-

vided with grooves or sockets B¹ adapted to fit upon the water circulating tubes 10 and the brick is of such a dimension that when placed with the socket B¹ upon the tube the outer face or end of the brick rests firmly against the side sheet 3 of the firebox and the brick is thereby retained securely in its desired position. The upper surface of the brick B is inclined upwardly and outwardly and is provided with a plurality of spaced longitudinal ribs B² separated by longitudinal grooves B³, and on account of the upper surface of the brick B being on an incline the ribs B² are at different heights and at different distances from the side sheet. This brick B is substantially triangular in cross-section, the base of the triangle being set against the side sheet and the point of the triangle having the groove or socket B¹ and resting upon the tube.

In the drawings I have shown the arch bricks A in the form of rectangular slabs and they are of such a length that when the outer ends of the bricks are placed upon the abutment bricks the inner ends of the bricks will abut substantially on the center line of the firebox and the bricks will be in upwardly inclined positions forming a V-shaped arch proper, supported by the abutment bricks. These bricks A are each provided with a projection A¹ upon their lower ends adapted to enter any one of the grooves B³ and engage the corresponding projection B² and thereby interlock the bricks A with the bricks B and retain the bricks A in their adjusted positions. It will now be evident that the arch proper can be positioned within the firebox at different heights, depending upon which of the grooves B² are made use of; and, further, that it can be adjusted in width by the same method to accommodate itself to fireboxes of different widths and yet not vary greatly from the desired elevation of the arch proper.

In installing arches in fireboxes in accordance with my invention, I first place the abutment bricks B upon the tubes and filling the space between the tubes and the side sheets, and I then place a pair of the bricks A adjacent to the flue sheet and resting at their lower ends upon a companion pair of the abutment bricks. The tubes being inclined downwardly toward the flue sheet the two bricks A will be inclined forwardly toward the flue sheet and their abutting upper ends will be in contact with the flue sheet or may be spaced therefrom by means of the small spacing block C which is placed between the apex of the arch and the flue sheet and is held in position by the weight of the arch pressing it against and holding it in firm contact with the flue sheet. Suitable spacing bricks C' lie between the flue sheet 2 and the abutment bricks B to support the latter at the proper distance from the flue

sheet. The arch is completed by adding further spans of the bricks A upon companion abutment bricks B until the arch is made of the desired length and height. The arch, as thus formed, comprises two inclined leaves or panels which rest at their outer edges upon the abutment bricks and rest against each other at their inner edges and are each formed on a number of the bricks A. These inclined leaves provide the arch with inwardly and oppositely inclined gas-deflecting under surfaces which are adapted to deflect the gases rising from the fuel bed as they flow upward and cause them to intermix and commingle and thereby enhance the complete combustion of the fuel. The inner ends of the bricks A are each provided with a half tongue A² and a half groove A³. The tongue on one brick is complementary to the groove on its opposite brick and they are adapted to mutually interlock the abutting pairs of bricks together at their inner ends and thereby retain these bricks in position. It is sometimes desirable to form the arch with subsidiary deflecting surfaces or gas-mixing pockets and for this purpose I sometimes alternate the bricks A with thin cover bricks D, as illustrated in Fig. 4, these cover bricks being formed to space the bricks A apart longitudinally in the firebox and fill the spaces between them, and are provided with suitable supporting ledges and shoulders for this purpose. This formation of arch provides it with a transverse shallow groove or cavity which is adapted to aid in the admixture of the firebox gases.

My invention is also adapted for installation in fireboxes which are not provided with water-circulating tubes and in Fig. 6 I have illustrated such an application of it. The abutment brick E therein shown is what might be termed a reversible brick. It has two inclined surfaces E¹ either one of which may be made use of upon which to support the arch proper and each is provided with the longitudinal grooves B³ and the ribs B² and in order to support these bricks in their position upon the side sheets I provide supporting lugs 12 secured to the side sheets and adapted to project into sockets or openings E² provided in the outer surfaces E³ of these bricks. In the arch, as illustrated in Fig. 6, I have shown the arch proper as being made up of arch bricks F, similar to the bricks A; and cover bricks G, similar to the cover bricks D, thus clearly showing that arches to fulfill various conditions can be produced and can be arranged to accomplish the most economical results.

As many modifications of my invention will readily suggest themselves to one skilled in the art, I do not limit or confine my invention to the specific structures herein shown and described.

Having thus fully described my invention,

I claim as new and desire to secure by Letters Patent:

1. A locomotive boiler firebox, in combination with inclined water-circulating tubes therein arranged adjacent to the side sheets 70 of the firebox, refractory arch abutments resting on said tubes and against the adjacent side sheets, said abutments having their upper surfaces provided with a plurality of arch engaging projections arranged at different heights, and a refractory arch in said firebox composed of two transverse leaves interlocked at their inner edges and resting at their outer edges upon said abutments, their outer edges being provided with complementary projections adapted to engage the different projections of the abutments and thereby place the arch at different heights, substantially as described.

2. An adjustable arch for locomotive 85 boiler fireboxes, comprising refractory abutment members having a plurality of arch-engaging projections arranged at different heights upon their upper surfaces and supported adjacent each side of the firebox, and a V-shaped arch proper each side thereof being provided on its lower edge with abutment-engaging projections, the upper edges of the two sides being arranged in interlocking engagement at substantially the center line of the firebox, substantially as described.

3. An adjustable arch for locomotive fireboxes comprising refractory arch supporting abutments and supports upon which 100 said abutments are carried adjacent to the side sheets of the firebox, said abutments having upwardly and outwardly inclined surfaces provided with longitudinally arranged ribs forming arch-engaging projections, and a V-shaped arch proper spanning between opposite abutments and supported thereby, the arch comprising two inwardly inclined leaves, the lower edges thereof having longitudinal ribs adapted to engage with the arch supporting ribs on the abutments to hold the arch at different heights, and the inner edges of said leaves being formed for mutual interlockment, substantially as described.

4. A refractory abutment brick for use with adjustable arches in locomotive fireboxes, composed of refractory material, presenting a flat back and having an upper stepped surface presenting several interlocking 110 projections, substantially as described.

5. A locomotive boiler firebox, in combination with a refractory arch therein, comprising a plurality of transverse rows of 120 refractory members, each row consisting of two oppositely disposed abutment members, means supporting said abutment members in position upon the side sheets of the firebox, and two oppositely inclined arch members having complementary interlocking 130

grooves and tongues upon their inner ends and said arch members and abutment members having complementary longitudinally arranged tongues and grooves and so arranged that the lower ends of said arch members can be placed at different distances apart upon said abutment members and held in such position, substantially as described.

6. A locomotive boiler firebox, in combination with an inclined front arch therein comprising refractory abutment members and means for supporting said members in oppositely disposed positions upon the two side sheets of the firebox, said members having a plurality of longitudinally arranged arch-engaging ribs or projections and oppositely inclined arch bricks formed to abut and interlock at their inner ends, and abutment engaging projections at their lower ends adapted to engage one of the several longitudinal ribs of the abutment members, and hold said arch members in their adjusted positions, substantially as described.

7. A locomotive boiler firebox and its side sheets, in combination with inclined arch tubes substantially parallel with said sheets,

refractory abutment bricks arranged between and supported by respective tubes and side sheets and presenting inwardly and downwardly inclined tops each having a plurality of projections at various heights, and refractory arch body bricks thereby adjustably secured upon the tops of said abutment bricks.

8. A locomotive boiler firebox and its side sheets, in combination with inclined arch tubes substantially parallel with said sheets, refractory abutment bricks wedgingly arranged between and supported by respective tubes and side sheets and presenting inwardly and downwardly inclined tops each having a plurality of projections at various heights, and refractory arch body bricks thereby adjustably secured upon the tops of said abutment bricks.

In testimony whereof, I have hereunto set my hand, this 5th day of December, 1911, in the presence of two subscribing witnesses.
